Primary Examiner — Carla Jobe Wright(74) *Attorney, Agent, or Firm* — Morgan, Lewis & Bockius LLP(57) **CLAIM**

The ornamental design for a case for cellular phone, as shown and described.

DESCRIPTION

FIG. 1 is a front, right side, perspective view of a case for cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof showing the hinge feature in an open configuration with environmental subject matter depicted in dash-dash broken lines; and,

FIG. 9 is an enlarged detail view taken from FIG. 8.

The dot-dash broken lines in FIGS. 8 and 9 delineate a detail of the design that is shown on an enlarged scale in FIG. 9. The dash-dash broken lines in FIGS. 8 and 9 depict environmental subject matter that forms no part of the claimed design.
